United States Patent Office

Des. 228,692
Patented Oct. 16, 1973

228,692

NASAL CANNULA

William R. King, Denver, Colo., assignor to
Sandoz-Wander, Inc., Hanover, N.J.

Filed June 2, 1971, Ser. No. 149,408

Term of patent 14 years

Int. Cl. D24—99

U.S. Cl. D83—1 G

FIG. 3

FIG. 1 is a front elevation of the nasal cannula;
FIG. 2 is a side elevation view of the nasal cannula,
looking to the left in FIG. 1;

FIG. 3 is an isometric view of the nasal cannula.
The broken lines are shown for illustrative purposes
only.

I claim:

The ornamental design for a nasal cannula, as shown
and described.
